UNITED STATES PATENT OFFICE.

ROBERT F. SCHLEICHER, OF ROCKVILLE CENTER, NEW YORK, ASSIGNOR TO LONDON
LIGHTINGWARES CORPORATION, A CORPORATION OF NEW YORK.

DESIGN FOR A GLASS LIGHTING UNIT.

Application filed January 22, 1926. Serial No. 16,216. Term of patent 3½ years.

To all whom it may concern:

Be it known that I, ROBERT F. SCHLEICHER, a citizen of the United States, and residing at Rockville Center, in the county of Nassau and State of New York, have invented a new, original, and ornamental Design for Glass Lighting Unit, of which the following is a specification, reference being had to the accompanying drawings, forming part hereof.

The figures of the drawing show the design of the article. Fig. 1 is a side view and Fig. 2 is a bottom view of the glass lighting unit.

I claim:

The ornamental design for a glass lighting unit, as shown.

ROBERT F. SCHLEICHER.
